(57) **CLAIM**

The ornamental design for a plant holder as shown and described.

DESCRIPTION

FIG. 1. is a top, rear, and right perspective view of a plant holder showing the design;

FIG. 2. is a bottom, front, and left perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof; and,

FIG. 8. is a bottom plan view thereof.

The broken lines depict portions of the plant holder that form no part of the claimed design.

1 Claim, 8 Drawing Sheets
